UNITED STATES PATENT OFFICE

147,502

DESIGN FOR A FLOOR SANDING MACHINE OR THE LIKE

Frank J. Koenig, Chicago, Ill., assignor to Skil-saw, Inc., Chicago, Ill., a corporation of Delaware

Application December 6, 1945, Serial No. 124,430

Term of patent 14 years

(Cl. D9—2)

To all whom it may concern:

Be it known that I, Frank J. Koenig, a citizen of the United States, residing at Chicago, in the county of Cook and State of Illinois, have invented a new, original, and ornamental Design for a Floor Sanding Machine or the like, of which the following is a specification, reference being had to the accompanying drawing, forming part thereof.

In the drawing:

Fig. 1 is a view in perspective of a floor sanding machine showing my new design.

Fig. 2 is a view in side elevation of the same.

Fig. 3 is a view in front elevation of the same.

The other side, not shown, is substantially like the side shown except that said side does not have the peripheral rib and pulley wheels.

I claim:

The ornamental design for a floor sanding machine or the like, as shown and described.

FRANK J. KOENIG.
